Primary Examiner — Karen S Acker(74) *Attorney, Agent, or Firm* — Jean C. Edwards, Esq.; Edwards Neils PLLC(57) **CLAIM**

The ornamental design for a display screen for a digital camera, as shown and described.

DESCRIPTION

FIG. 1 is a first image of a display screen for a digital camera showing my new design;

FIG. 2 is a second image thereof; and,

FIG. 3 is a third image thereof.

The process or period in which one image transitions to another image forms no part of the claimed design.

The appearance of each image sequentially transitions between the images shown in FIGS. 1 through 3. The process or period in which one image transitions to another image forms no part of the claimed design. Within the transition, the larger rectangle and the crosses in FIGS. 1 through 3 show contrast in shade.

The claimed portion of the display screen for digital camera includes a larger rectangle showing an imaging area and a small rectangle showing an auto-focusing area and crosses showing area points each allowing the auto-focusing area to be set.

The broken lines in the drawing represent portions of the display screen for a digital camera that form no part of the claimed design.
